(57) **CLAIM**

The ornamental design for a modular spare tire side mount for accessories, as shown and described.

DESCRIPTION

FIG. 1 is a top perspective view of a modular spare tire side mount for accessories, showing my new design as mounted to a tire;

FIG. 2 is a top perspective view thereof, illustrated with the tire omitted for clarity of illustration;

FIG. 3 is a front elevational view of FIG. 2, the rear elevational view being a mirror image thereof;

FIG. 4 is a left-side elevational view of FIG. 2;

FIG. 5 is a right-side elevational view of FIG. 2;

FIG. 6 is a top plan view of FIG. 2;

FIG. 7 is a bottom plan view of FIG. 2; and,

FIG. 8 is a bottom perspective view of FIG. 2.

The broken lines showing of the tire and tire face accessory mount, in FIG. 1, illustrate the environment of the claimed design and forms no part thereof. The remaining broken lines in the drawings illustrate portions of the modular spare tire side mount for accessories and form no part of the claimed design.
